CIGAR KNURLER

George Hoeffle, Philadelphia, Pa., assignor to International Cigar Machinery Company, a corporation of New Jersey

Application October 23, 1937, Serial No. 170,569

18 Claims.

This invention relates to a cigar knurler for smoothing the head ends of cigars and laying the wrapper flag smoothly thereon, and more particularly to an improvement in knurlers whereby more knurling time for automatic knurling is obtained and whereby cigars may be held firmly during the greater part of the knurling time.

Automatic knurlers for knurling cigars as they are delivered from the cigar machine have generally been of the type disclosed in U. S. Letters Patent to R. E. Rundell, No. 1,582,545, in which the knurler is simply placed alongside the path of the cigars through or from the machine, and whatever relatively short time is left over from the other operations on the cigar at that part of the machine is used for knurling. Also, the knurler is ordinarily used for locating the cigar for a concurrent operation, as for example the operation of trimming the other end of the cigar. In cigar machines which include such a knurler arrangement as standard equipment, and which comprise probably a majority of the cigar machines in use at the present time, the conventional timing allows about 30° of the machine 25 cycle of 360° for the knurling operation.

Further, since the cigars are usually located by the pressure of the knurler endwise of the cigar to slide the same, the operation of such a machine is subject to the disadvantage that the means which grips the cigar at this position to hold it for knurling, must grip it rather lightly, to permit sliding of the cigar without injury to the delicate cigar wrapper, and hence the pressure exerted by the knurler is quite limited, and is somewhat inadequate at times. As a result, especially with certain shapes of cigars and types of wrappers, it is necessary to hand-knurl some or all of the cigars issuing from the machine. For this reason a hand knurler is disclosed in the above-mentioned Rundell patent.

An object of the present invention is to overcome the aforesaid difficulties and to make the machine knurling capable of keeping up with greater machine speeds and still to obtain a longer knurling period, at the same time eliminating hand knurling completely.

It is also an object to accomplish the foregoing desirable results in such a manner that the improved construction will cooperate with, and take advantage of, a knurler structure available and in common use on conventional cigar machines.

A further object is to avoid the necessity for providing positively acting mechanism for transferring the partially knurled cigar from the pri-

(Cl. 131—29)

mary knurling station to the secondary knurling station, by so organizing the several co-operating means that when the partially knurled cigar is released by the gripping means operating at the primary knurling station, it will be gravity biased toward the secondary knurling station, and will be concurrently disposed suitably for the secondary knurling operation, by virtue of such gravity bias, without the need for further 10 co-axial displacement, thus obviating all interference between knurlers and transfer devices, and all mechanism designed to clear transfer devices from the path of the secondary knurler, this result being attained by such elimination of interfering transfer mechanism.

Another object of the invention is to provide means for so co-ordinating the devices for gripping the cigar at the primary knurling station with means for locating the same partially knurled cigar properly at the secondary knurling station, that the release of the grip at the first station is automatically accompanied by setting a stop at the secondary station, this being accomplished preferably by connected primary gripping means and secondary stop means operating at alternating positions of a unitary oscillating structure.

Another object of the invention is to so organize the mechanism for performing the secondary knurling operation upon a cigar that has been already knurled in a primary operation, that while the first knurling may occupy a relatively small portion, say less than 90° of the conventional machine cycle of 360°, per contra, the secondary knurling operation upon the same cigar may avail of over 90° of the immediately succeeding machine cycle, and may apply more pressure to hold the cigar and knurl it, thus increasing greatly the aggregate time of knurling and the efficiency of the total knurling operation.

With these and other objects, the invention consists of certain constructions and combinations of which an illustration is herein set forth, and then pointed out in the accompanying claims.

In the accompanying drawings:

Fig. 1 is a front elevation of the improved knurling device;

Fig. 2 is a view in sectional plan of the same, taken on the line 2—2 of Fig. 1;

Fig. 3 is an end elevation of the same taken in the direction indicated by the arrows at the ends of the line 3—3 of Fig. 2;

Fig. 4 is also an end elevation of the same taken in the opposite direction, as indicated by

the arrows at the ends of the line 4—4 of Fig. 1.

Fig. 5 is a fragmentary detail view of a schematic character in front elevation, and in continuation of Fig. 1, showing the cam shaft and the parts operated thereby: and

Fig. 6 is a similar view, in transverse sectional elevation, taken on the line 6—6 of Fig. 5.

Referring to the drawings, 5 indicates a re-roller drum of well-known construction and operation, which is adapted to re-roll a wrapped cigar. This re-roller drum 5 is given an oscillating movement by means of a pinion 6 mounted on shaft 7, the pinion 6 being rocked by a gear rack 8 having a reciprocating movement derived from a lever 85 fulcrumed at 86 upon a frame part 87 (Fig. 6), and having a cam follower 84 running in a face cam groove 83 of a disk cam 82 fixed upon the shaft 81, of the cigar making machine with which the device is used. Shaft 7 is supported in bearings of a bracket 9 rising from the bed 10 of the cigar machine proper. Co-acting with the re-roller drum 5 is a re-roller concave or chute 11 attached at its lower ends to a lug 12 fastened to a supporting shaft 13 held by a pair of brackets 14 mounted on the bed 10.

The wrapped cigars are automatically delivered to the re-rolling device just described, at the bevel shaped end 15 of the re-roller concave 11 (Fig. 2) and are rolled to a position within the range of the first knurling device where the cigar is held by means of a pair of supporting fingers 16 and a clamp finger 17. Supporting fingers 16 (see Fig. 3), are mounted on a horizontal shaft 18 supported in bearings carried by an arm 19 of a bracket 20 fastened to the stationary shaft 13. To the shaft 18 is fastened an operating lug 21 projecting into the path of a pin 22 (Fig. 3) mounted on the lower portion of the oscillating gear rack 8.

A tension spring 23 (Fig. 3) is provided for the purpose of permitting supporting fingers 16 to project through slots 24 (Fig. 2) of the chute 11 into the path of the re-rolled cigar after the same is discharged from the re-roller drum 5. After this primary knurling operation, and upon the engagement of pin 22 with operating lug 21, the supporting fingers 16 are forced to retreat beneath the surface of the chute 11, thus permitting the cigar to roll down the inclined portion of chute 11 to the second knurling station, defined by the secondary knurler 48, to be described more at length. An adjusting and stop screw 25 (Fig. 3) is provided for the correct setting and adjusting of supporting fingers 16.

Clamping finger 17 (Fig. 3) is mounted on a rock shaft 26 supported in bearings at the upper end of an arm 27 on bracket 20. To shaft 26 is fastened a cam lug 28 which, when engaging with a roller 29, causes shaft 26 to turn partly and thereby effects a lifting of the clamp finger 17. The roller 29, (Figs. 1 and 2), by means of a stud 30, is pivoted to an operating arm 31 fulcrumed on a stud 32 (Fig. 1) held by a supporting bracket 33 mounted on bed 10. Arm 31 is oscillated by means of a link 34 (Figs. 1, 3, 5 and 6) extending from a cam lever 35 having a follower 90 engaging with a proper cam 89 on a shaft 81 of the cigar machine, the lever 35 being pivoted at 91 upon a part 92 of the frame. To stud 30 of arm 31 is pivoted a roller 36 (Fig. 2) engaging with a collar 37 mounted on a knurler shaft 38 of the primary knurler station. Said knurler shaft 38 is constantly driven by means of a conventional worm gear 39 (Fig. 2) engaging with a worm 40 mounted on a shaft 41 connected

with the main drive of the cigar machine. Shaft 38 is supported in suitable bearings carried by a housing 42 attached to bracket 43, fastened to the bed 10 of the machine.

5 When a cigar arrives at this primary knurling station and is held by the above-described action of the supporting fingers 16 and clamping finger 17, the rotating knurler shaft 38, carrying a knurler head 44 is moved horizontally by means of arm 31 and roller 30 towards the cigar, until knurler head 44 engages with the head end of the same, causing the wrapper flag to be smoothly knurled onto the head of the cigar. The horizontal movement of the knurler moves the cigar bodily to the position shown in Fig. 2, where properly positioned knives 79 cut off that end. Such movement of the cigar is permitted by the yielding pressure of the spring-biased clamping fingers 16, 17, and this may be regulated so that no injury will result from the sliding movement to the delicate wrapper of the cigar.

Due to the fact that in this construction the supporting fingers 16, through lug 21 (Fig. 3), are operated by means of the pin 22, mounted on 25 the reciprocating gear rack 8 which oscillates re-roller drum 5, the primary knurling time at this station is very limited, occupying say 30° of the total machine cycle of 360°. Therefore, in pursuance of the present invention, after the retreat 30 of the knurling and clamping means at this primary knurling station, the cigar, freed by such retreat, rolls down the inclined surface of the concave chute 11 to a secondary knurling station, where the cigar is arrested by a detent device 35 formed by a pair of stop fingers 46 and a clamp plate 47. Stop fingers 46 are mounted on the rock shaft 26, which, as illustrated in Fig. 3, causes stop fingers 46 to descend as soon as the clamp fingers 16 and 17 are cleared from the cigar at 40 the primary knurling station.

The secondary knurling station is provided with a knurler head 48 which is shown as of the same type and design as the one used in the first knurling operation. Said knurler head 48 is mounted 45 in similar fashion on a horizontally reciprocating knurler shaft 49 (Figs. 1 and 2) supported in suitable bearing lugs at the upper ends of posts forming part of a frame 50 fastened to bed 10. Shaft 49 is also constantly rotated by means of a 50 pulley 51 and a belt 52 from a pulley 53 mounted on the knurler shaft 38 of the primary knurler. Shaft 49 carries a collar 54 with which engages a roller 55 pivoted to an operating arm 56 loosely mounted on a stud 57 (Figs. 1 and 4) held by bracket 50. To arm 56 is also pivoted a roller 58 engaging with a cam 59 mounted on a shaft 60 driven by means of a sprocket 61 and a chain 62 from a sprocket 60 on the main drive 81 of the cigar machine (Figs. 5 and 6). A tension 55 spring 63 (Fig. 1) is provided, for the purpose of keeping roller 58 in steady contact with cam 59. Shaft 60 is also supported in suitable bearing lugs of bracket 50. To arm 56 is also pivoted a link 64 which, at its opposite end, is provided 60 with a slot 65 entered slidably by a supporting pin 66 extending from a bearing lug 67 of bracket 50. Link 64 carries a cam piece 68 with which engages a roller 69 pivoted to a clamping lever 70, which in turn controls the up and down motion of clamp plate 47. Lever 70 is loosely mounted on a stud 71 (Fig. 1) held by a lug 72 of an upright bearing post 67. The opposite, free end of clamping lever 70 extends over the concave chute 11, and carries a guide bushing 73 (Fig. 1) slidably supporting the vertical clamping stem 75

74, to the lower end of which is fastened the clamp plate 47, while to the upper end of the same is attached a guide plate 75 carrying a guide pin 76 engaging with a suitable hole in lever 70 to prevent clamp plate 47 from turning. A pressure-adjusting spring 77 (Figs. 1 and 3), placed between arm 70 and clamp plate 47, is provided, as already noted, for the purpose of preventing injury to the delicate wrapper of the cigar while the latter is held by clamp plate 67, and when the secondary knurler head 48 engages the cigar for the final knurling operation. A tension spring 78 (Fig. 1) anchored to lever 70 assures a steady contact of roller 69 and cam piece 68. The pressure of the clamping member 47 is adequate to prevent retreat of the cigar lengthwise when pressure is applied by the secondary knurler 48.

It will be seen from the foregoing disclosure that the movements of the chain 62, the rack 8 and the lever 35 are all coordinated by their connections with a common driving shaft 81, so that by the provision of suitable cams thereon, as those already described at 82 and 89, the operation of the re-roller 5, the knurlers 44 and 48, and the grippers 16-17 and 46-47, together with their associated mechanisms, will all be carried out in properly timed relation to secure the various results hereinbefore described, and pointed out in the claims.

What is claimed is:

1. In a cigar machine of the class described, knurling mechanism adapted to perform a plurality of exclusively mechanical knurling operations upon each of an indefinite series of cigars, successively, said mechanism including means to locate the cigars individually at a knurling position and simultaneously to perform a light knurling operation on the cigar so positioned, means to hold the cigar more firmly for a further knurling operation, and means to discharge the completely knurled cigar from said mechanism.

2. In a cigar machine of the class described, knurling mechanism comprising means adapted to receive each cigar and forward it in a predetermined path, a primary knurling means adapted to locate and knurl the head of each cigar so forwarded, at a primary knurling station disposed transversely of said path, a secondary knurler means, at an advanced knurling station; for completing the knurling of said cigar; means to forward the cigar from station to station; gripper devices at each of said stations, and mechanism connected to said gripper device at the primary knurling station and adapted to operate said secondary gripper to grip the cigar previously released by said primary gripper.

3. In a cigar machine of the class described, knurling mechanism comprising means adapted to receive each cigar and forward it in a predetermined path, a primary knurling means adapted to locate and knurl the head of each cigar so forwarded, at a primary knurling station disposed transversely of said path, a secondary knurler means, at an advanced knurling station for completing the knurling of said cigar, and devices to forward the cigar from station to station, including a detent device for arresting each cigar at said secondary knurling station and also including means for tripping said detent device to permit the discharge of each completely knurled cigar in time with the forwarding of its successor from the primary knurling station to the secondary knurling station.

4. In a cigar machine of the class described, knurling mechanism comprising means adapted

to receive each cigar and forward it in a predetermined path, a primary knurling means adapted to knurl the head of each cigar so forwarded, at a primary knurling station disposed transversely of said path, and a secondary knurler means, at an advanced knurling station, for completing the knurling of said cigar, means for forwarding the cigars from station to station including a detent device for arresting each cigar at said secondary knurling station; and means for tripping said detent device to permit the discharge of each completely knurled cigar in time with the forwarding of its successor from the primary knurling station to the secondary knurling station, said detent device being formed as an oscillating element having an arm provided with a cigar-detaining member, and having another arm extending beyond the axis of oscillation and provided with a gripping member adapted to aid in clamping a cigar at said primary knurling station.

5. In a cigar machine of the class described, knurling mechanism comprising means adapted to receive each cigar and forward it in a predetermined path, a primary knurling means adapted to knurl the head of each cigar so forwarded, at a primary knurling station disposed transversely of said path, and a secondary knurler means, at an advanced knurling station for completing the knurling of said cigar, and mechanism for forwarding the cigars from station to station, said forwarding mechanism being constructed and arranged to produce a relative axial movement between said knurlers and said cigars to bring the same into operating engagement with each other, to provide a total knurling period longer than that permitted at a single station by the operating cycle of the machine; a detent device for arresting each cigar at said secondary station; means for gripping said cigar at each station during each knurling operation; and means for tripping said detent device to permit the discharge of each completely knurled cigar in time with the approach of its successor.

6. In a cigar machine of the class described, knurling mechanism comprising means adapted to receive each cigar and forward it in a predetermined path, a primary knurling means adapted to knurl the head of each cigar so forwarded, at a primary knurling station disposed transversely of said path, and a secondary knurler means, at an advanced knurling station for completing the knurling of said cigar, and mechanism for forwarding the cigar from station to station, said forwarding mechanism being constructed and arranged to produce a relative axial movement between said knurlers and said cigar to bring the same into operating engagement with each other, to provide a total knurling period longer than that permitted at a single station by the operating cycle of the machine; a detent device for arresting each cigar at said secondary station; means for gripping said cigar at each station during each knurling operation; and means for tripping said detent device to permit the discharge of each completely knurled cigar in time with the approach of its successor; said detent device being formed as an oscillating ele-

70 ment having an arm provided with a cigar-arresting member, and having another arm extending beyond the axis of oscillation and provided with a grip device adapted to aid in holding or clamping a cigar at said primary knurling station.

7. In a cigar machine from which cigars are delivered in succession, the combination with means for receiving and knurling the delivered cigars comprising mechanism forwarding the cigars along a predetermined path, a yielding gripper so arranged as to grip the cigars while permitting endwise movement of the cigar in its grip without injury to the same, a primary knurler, means for giving said knurler a locating movement to move a cigar to a predetermined endwise position in the gripper to locate the same while knurling the cigar, a secondary knurler arranged to act on the cigar forwarded from said primary knurler, and means for preventing endwise movement of the cigar during the operation of said secondary knurler to complete the knurling of said cigar.

8. In a cigar machine from which cigars are delivered in succession, the combination with means for receiving and knurling the delivered cigars, comprising mechanism forwarding the cigars along a predetermined path, a yielding gripper so arranged as to grip the cigars seriatim while permitting endwise movement of each cigar in its grip without injury to the same, a primary knurler, means for giving said knurler a locating movement to move the cigar to a predetermined endwise position in the gripper to locate the same while knurling the cigar, a secondary knurler arranged to act on the cigar forwarded from said primary knurler and means for preventing endwise movement of the cigar during the operation of said secondary knurler to complete the knurling of said cigar, means intermittently operating the gripper at said primary knurler to alternately grip and release a cigar and mechanism connected to said primary gripper to operate said means for preventing endwise movement to grip the cigar previously released by said primary gripper.

9. In a cigar machine from which cigars are delivered in succession, the combination with means for receiving and knurling the delivered cigars; of means forwarding the cigars along a predetermined path; a yielding gripper so arranged as to grip the cigars seriatim while permitting endwise movement of each cigar in its grip without injury to the same; a primary knurler; and means for giving said knurler a locating movement to move the cigar to a predetermined endwise position in the gripper to locate the same while knurling the cigar; said yielding gripper including a rocker element mounted pivotally intermediate its ends, and formed with arms extending oppositely from said pivot, one of which arms is formed with a member of said gripper, and the opposite arm is formed with a detent member adapted to intersect said path at an advanced position, said rocker element being so disposed that each cigar may be released by rocking movement of said element around its pivot to withdraw said grip member from the cigar at the primary knurling station, and at the same time said detent member will be moved into the path of forwarding of said cigar to arrest the same, thereby defining a secondary knurling station; a gripper device arranged to grip the cigars seriatim at said secondary knurling station when so arrested, and acting with adequate firmness to hold each cigar against endwise movement during a secondary knurling operation; and a secondary knurler adapted to act on the cigar while so held.

10. An attachment having the features claimed in claim 1, in which said mechanism comprises a rocking control element provided at its upper

end with a clamping member and at its lower end with a detent member, said members being alternatingly moved into operative position and inoperative position, by rocking said element, the clamping member acting to clamp a cigar at the primary knurling position, and the detent member acting to hold the same cigar for the further knurling operation.

11. In a cigar machine including mechanism from which cigars are delivered in succession, the combination with said mechanism of an inclined chute adapted to receive and forward each cigar so delivered; a primary knurling means adapted to knurl the head of each cigar so forwarded at a primary knurling station disposed transversely of said chute; and a secondary knurler means for completing the knurling of said cigar at a lower knurling station to which the same cigar is gravity biased along said chute when released by said primary knurling means.

12. An attachment for a cigar machine of the class described, having mechanism from which cigars are delivered in succession; said attachment comprising a primary knurling means adapted to receive seriatim each cigar so delivered, and acting to knurl its head; a secondary knurler means for receiving said partially knurled cigar from said primary knurling means and acting to complete the knurling of said cigar; and a chute along which each cigar is gravity biased to descend to the secondary knurling station when released by said primary knurling means.

13. An attachment having the features claimed in claim 12, in which said chute is spanned in the direction of travel of said cigars by a rocking control element provided at its upper end with a clamping member and at its lower end with a detent member, said members being alternatingly moved into operative position and inoperative position by rocking said element, the clamping member acting to clamp a cigar at the upper or primary knurling station, and the detent member acting to arrest the same cigar at the lower or secondary knurling station.

14. An attachment having the features claimed in claim 12, in which said chute is spanned in the direction of travel of said cigars by a rocking control element provided at its upper end with a clamping member and at its lower end with a detent member, said members being alternatingly moved into operative position and inoperative position by rocking said element, the clamping member acting to clamp a cigar at the upper or primary knurling station, and the detent member acting to arrest the same cigar at the lower or secondary knurling station, and means to rock said control element, whereby it is constituted the exclusive control means for regulating feeding movements of said cigars successively from said primary knurling station to said secondary knurling station.

15. In a cigar machine including re-rolling means from which cigars are delivered in succession; the combination with said re-rolling means of a chute adapted to receive seriatim each cigar so delivered; a primary knurling means adapted to knurl the head of each cigar so delivered to the chute at a primary knurling station disposed transversely of said chute; and a secondary knurler means for completing the knurling of said cigar at a lower knurling station to which the same cigar is gravity biased along said chute when released by said primary knurling means.

16. The novel method of machine knurling a

cigar, said method including a first knurling of each cigar, said first knurling occupying a relatively small proportion of the operating cycle of the machine, to allow time for other operations during the same cycle, and a secondary knurling operation which occupies a relatively large proportion of the next succeeding operating cycle of said machine.

17. The novel method of machine knurling a cigar, said method including a first knurling of each cigar, said first knurling occupying a relatively small proportion of the operating cycle of the machine, to allow time for other operations during the same cycle, and a secondary knurling operation which occupies a relatively large proportion of the next succeeding operating cy-

cle of said machine, said first knurling occupying less than 90° of the conventional machine cycle of 360° and said secondary knurling operation occupying more than 90° of the immediately succeeding machine cycle, whereby each cigar is knurled to an extent aggregating over 90° of a machine cycle.

18. In a cigar machine, mechanism for performing a finishing operation upon a cigar, mechanism coordinated with said first-named mechanism for performing a plurality of exclusively mechanical knurling operations upon said cigar, and mechanism to cause relative movement between said cigar and knurling mechanism lengthwise of the cigar axis for knurling.

GEORGE HOEFFLE.
